METHOD FOR PRODUCING LUBRICATING OIL

Ulric B. Bray, Palos Verdes Estates, Calif., assignor to Union Oil Company of California, Los Angeles, Calif., a corporation of California

Application January 26, 1935, Serial No. 3,613

15 Claims. (Cl. 196—34)

This invention relates to the production of lubricating oils from crude oils containing asphalt and wax and is a continuation in part of my application Serial No. 486,724, filed October 6, 5 1930, and a continuation in part of my application Serial No. 694,839, filed October 23, 1933, which was divided from my application Serial No. 466,189 filed July 7, 1930.

This invention is described but not claimed in 10 my copending applications Serial No. 597,419 filed March 7, 1932; Serial No. 625,562 filed July 29, 1932; Serial No. 625,563 filed July 29, 1932; Serial No. 650,995 filed January 10, 1933; Serial No. 693,644 filed October 14, 1933; Serial No. 707,641 15 filed January 22, 1934; Serial No. 707,642 filed January 22, 1934; Serial No. 721,602 filed April 20, 1934; and Serial No. 749,649 filed Oct. 23 1934. The invention is also described but not claimed in 20 my Patents 1,944,491 and 1,949,989 which are also 25 divisions of my copending application Serial No. 466,189 filed July 7, 1930.

It has been discovered that superior lubricating oils and asphalts can be obtained from crude oil by causing separation of the lubricating oil from 25 the asphalt at temperatures below that at which deleterious changes are induced in the oil.

It has been found that if oil containing asphalt is heated in the presence of the asphalt, the latter 30 catalyzes certain reactions in the oil which result 35 in the destruction of those characteristics of the lubricating oils which are most desirable.

It has been found advisable to cause the separation of asphalt from the oil by means of volatile solvents which are capable of dissolving the 35 oil and any wax and which do not dissolve the asphalt. Such solvents are light petroleum fractions, such as casinghead gasoline and naphtha and also petroleum fractions normally vaporous at ordinary temperatures and pressures. Other 40 solvents which may be used are alcohol, ether, mixtures of alcohol and ether, acetone, etc. I prefer to use as our volatile solvent a petroleum fraction obtained by the rectification of natural gasoline. The fractions are composed in the main 45 of propane and isobutane. A typical analysis of such a fraction is 6.72% ethane, 72.2% propane and 19.91% isobutane and 1.17% normal butane. It will be understood, however, that these merely 50 illustrate the type of fraction used and the composition may vary.

In order to cause the extraction with this liquid fraction, the solution is maintained at a pressure sufficient to maintain the propane liquid at ordinary temperatures. The fraction above described 55 is liquid at ordinary temperatures at about 125

lbs. The extraction of the oil from the asphalt at such pressures results in an asphalt substantially free of oil and a solution of oil in the liquid petroleum fraction. This solution contains substantially all the wax present in the crude oil.

It has also been found that oil containing asphalt and impurities such as wax may be first freed from the asphalt by a primary extraction with a light solvent such as the solvent described above and that the impurities such as wax, may then be removed at a suitable temperature by the aid of a heavier solvent, such as naphtha in which the wax is substantially insoluble at the low temperature employed. By heavier solvent, I mean one of higher boiling point than the light solvent previously described.

Advantage is taken of the high volatility of the light solvent to cause a cooling of the oil upon a release of pressure to produce the separation of the contained wax. A further advantage in cooling the oil in this manner is to bring the oil to a proper temperature for acid treatment. By acid treatment, I intend to include treatment with acid followed by the step of neutralization and/or clay treatment.

If a large proportion of the propane is removed from the solution after the asphalt has been separated, the remaining solution becomes too viscous and not of sufficiently low specific gravity to permit satisfactory behavior in the dewaxing operation which is conveniently accomplished in a centrifuge. Difficulties are also encountered in chemically treating oils of high viscosity. My invention avoids these difficulties by mixing the oil with naphtha before dewaxing, 35 to reduce the viscosity and place the oil in proper condition for dewaxing. The reduced viscosity is also advantageous in chemical treatment of the oil. If naphtha is expanded at very low pressure into the oil prior to dewaxing, it may also 40 have a cooling effect similar to that caused by the expansion of the propane. By naphtha, I mean those petroleum fractions which vary from kerosene to light fractions of gasoline, preferably a gasoline-like fraction having a specific gravity 45 of about 55° A. P. I. and a boiling range of about 200–300° F. Instead of naphtha I may use other solvents or diluents, for instance, benzol, alcohols such as methyl, ethyl, propyl, butyl alcohol or mixtures of the same, ketones such as acetone or di-ethyl ketone, chlorinated light hydrocarbons such as dichlorethylene, trichlorethylene or the like, or mixtures of benzol with acetone or other ketones, or mixtures of benzol and butanol or other alcohols.

- In addition to the power which the naphtha has of reducing the viscosity of the asphalt-free oil, it also is used as an extracting medium for wax or other material whose presence is deleterious in a finished, high grade lubricating oil. The naphtha, if used in sufficient quantities, acts as a solvent for the oil during the removal of the wax or other impurities in a manner similar to the action of the propane solution during the removal of the asphalt. By regulating the quantity, substantially oil-free wax may be precipitated. In comparing their volatility and specific gravity, the propane is considered to be the light solvent and the naphtha is the heavier solvent.
- An advantage in using both light and heavy solvents resides in the fact that the dewaxing may take place in the presence of the heavier solvent after the lighter, more volatile solvent has been evaporated with a consequent decrease in the temperature of the wax-containing oil.
- It is, therefore, an object of my invention to produce lubricating oil from oil containing asphalt and impurities by extracting the lubricating oil first with a light solvent, such as propane, to precipitate the asphalt and then extracting the oil from the impurities such as wax, with a heavier solvent such as naphtha.
- It is a further object to produce lubricating oil from the oil described above by maintaining pressure on the oil and light solvent during the extraction of the asphalt and to extract the impurities such as wax from the asphalt-free oil by means of a heavier solvent under reduced pressure.
- It is furthermore an object of my invention to produce lubricating oil from oil containing asphalt and wax, by mixing this oil with a solvent in which the lubricating oil fractions and wax are soluble, but in which the asphalt is insoluble, and subsequently separating the wax from the lubricating oil fractions in the presence of naphtha.
- It is a further object of this invention to mix the naphtha with the oil either in the presence of substantially all the propane used to precipitate the asphalt, or in the presence of only a portion of said propane, or the naphtha may be added after substantially all the propane has been separated from the oil and wax.
- It is a further object of this invention to produce lubricating oil from oil containing asphalt and wax by precipitating the asphalt with a solvent for the oil and wax and to chemically treat the oil either before or after removal of the wax from the oil, and either before or after the addition of naphtha to the oil and wax.
- Another object of this invention is to produce lubricating oil from oil containing asphalt and wax by mixing a volatile solvent therewith under pressure to precipitate the asphalt and dissolve the lubricating oil fractions and wax, separate the precipitated asphalt under pressure, and taking advantage of the highly volatile characteristics of the solvent by releasing the pressure and allowing the solvent to vaporize and consequently cool the oil and wax, thereby precipitating the latter, and to separate the wax from the oil in the presence of naphtha.
- Another object of the invention is to produce lubricating oil in the manner described above and to make further use of the volatility of the solvent by partially releasing the pressure on the oil, solvent and wax subsequent to the removal of the precipitated asphalt under pressure, whereby the oil, wax and the solvent which remain in

the liquid form are sufficiently cooled to be at the desired temperature for chemical treatment, and after chemical treatment, making use of the volatility of the remaining solvent by further releasing the pressure and precipitating the wax due to the consequent cooling. 5

The process will be more adequately understood by reference to the drawings which show preferred schematic arrangements of the apparatus to carry out the process described herein. 10

Fig. 1 is a schematic arrangement of apparatus in which the oil is first made asphalt-free and then is chemically treated in the presence of substantial quantities of solvent.

Figure 2 is a modification of the schematic 15 arrangement of apparatus shown in Figure 1.

Referring to Fig. 1, topped residuum from tank 40 is passed by pump 41 through line 42 where it meets a propane solution of lubricating oil coming through line 54. The propane and residuum pass through the turbulence or mixing coil 43 and then into decanter 44. The asphalt in the residuum is precipitated by the propane and settles to the bottom of decanter 44. The precipitated asphalt resembles a slurry and may be drawn off from the bottom of the decanter with sufficient liquid propane to permit pumping. 20

The asphalt propane slurry is passed through line 45, pump 46 and line 47 where it is mixed with fresh liquid propane from storage 48 sent via pump 49 and line 47. The mixture is then passed into mixing coil 50 and into decanter 51. If it is desired to produce an asphalt containing still less oil or wax, the countercurrent washing with propane may be extended to as many steps as desired. Decanters 44 and 51 and storage 48 are maintained at the same pressure by means of equilibrium lines 55 controlled by valves 56. The pressures in 44, 51 and 48 are sufficient to maintain the solvent in liquid state at ordinary temperatures. 30

The clear overflow from decanter 51 consisting of liquid propane in which is dissolved a small amount of oil is sent through line 52, pump 53 and line 54 to its connection with line 42 where it is mixed with the incoming topped residuum. The mixed residuum and propane pass through mixing coil 43 and into decanter 44 as described above. 35

The asphalt slurry from decanter 51 is drawn off through line 128 and pressure release valve 129. 50

The clear overflow from decanter 44, now consisting of a more concentrated solution of lubricating oil and propane, is next prepared for acid and alkali treatment at reduced temperature. A reduced temperature is very beneficial in the chemical treatment of certain types of oils. In order to lower the temperature of the propane solution, the pressure on the solution is decreased 60 to a value corresponding roughly to the vapor pressure of propane at the desired treating temperature and evaporation of the propane takes place until this temperature is reached, the pressure in the meantime being held constant by 65 automatic pressure regulating valves. A temperature of about 40° F. is desirable in the following chemical treatment and may be obtained by reducing the pressure on the propane solution to substantially 70 lbs. per square inch. 70

The propane solution from the top of decanter 44 is therefore passed through line 57 to the pressure release valve 58 and into expansion chamber 59 which is held at a predetermined pressure by means of automatic back pressure 75

regulating valve 61. The propane which has been vaporized in 59, in order to lower the temperature of the remaining oil solution, passes through line 60, valve 61 and line 106 to compressor 126 where 5 the propane vapors are compressed, liquefied and sent to propane storage 48 after cooling in cooler 127.

The cooled propane solution in expansion chamber 58 is sent through line 62 by pump 63 10 to turbulence or mixing coil 67 and thence to decanter 68. Sulfuric acid is introduced from tank 65 by means of pump 66 into line 64. The acid treated oil solution is decanted and the sludge is withdrawn through line 69. The oil is 15 sent by line 70 and pump 71 into turbulence or mixing coil 77 and thence to decanter 78. Water for use in washing the acid treated oil is introduced in line 78 from water storage 72 via pump 73, valve 74 and line 76. The washed oil is then 20 decanted and is removed from decanter 78 via line 80 and pump 81 into line 82. The wash water is removed from decanter 78 through line 79.

Alkali from alkali storage 83 is then admitted to line 82 via pump 84 and line 85. The oil and 25 alkali flow through turbulence coil 86 into decanter 87 from which the alkali sludge is removed via line 88. The decanted oil from 87 is next sent into line 89 by pump 88 and thence into turbulence coil 92. Wash water is also allowed 30 to enter said coil 92 by passage from water storage 72 via pump 73, valve 75, line 81 and line 88. From the turbulence coil 92, the material passes into decanter 93 from which the wash water is removed via 84. Pressure is maintained on the 35 decanters 88, 78, 87 and 93, as above described.

The treated oil solution leaving the treating group by means of line 86 is passed by pump 86 through a second expansion valve 97 where the pressure is released to that corresponding to 40 the dewaxing temperature. This pressure will be substantially atmospheric and its corresponding temperature will be about -35° F. Then the oil passes to expansion chamber 101 wherein propane is evaporated and returned by line 104 45 to storage 48. The oil, free of propane, leaves by 107 to a dewaxing operation and then to storage, not shown. If desired, naphtha may be added to the oil-propane solution prior to evaporating the propane to give sufficient fluidity during the removal of wax.

Since the separation of asphalt from the oil by distillation of the oil cannot be accomplished without destruction of the paraffin base characteristics of the oil, the process devised by me 55 for removal of the asphalt comprises its precipitation by means of solvents. Asphalt may be precipitated from oil by chemicals, such as sulfuric acid. I find however, that it is best precipitated by use of solvents in which the lubricating oil fractions are soluble but in which the asphalt is insoluble. Such solvents are alcohol, 60 ether, mixtures of ether and alcohol, acetone, volatile hydrocarbon solvents, such as casinghead gasoline and light naphthas. I find, however, 65 that the process is best carried out by the use of hydrocarbons which are normally in the vapor state at atmospheric pressure and temperature. Such hydrocarbons include propane, isobutane, butane, ethane, methane and mixtures thereof. 70 These may be obtained by rectification of casinghead gasoline by the so-called "stabilizing method" now conventional in the natural gas industry. They are the overhead thus obtained. They are liquefied by compression and cooling in 75 the conventional manner and drawn off into pres-

sure chambers where they are maintained in the liquid state until they are used. A typical analysis of such a fraction is 6.72% ethane, 72.20% propane, 19.91% isobutane and 1.17% normal butane and the necessary pressure to maintain the fraction in a liquid state is approximately 125 lbs. per square inch gauge at 73° F.

The oil stock containing asphalt is mixed with this liquid solvent under superatmospheric pressure and the mixture is allowed to settle to permit the precipitation of the asphalt. The solution of lubricating oil in the liquid solvent is withdrawn from the pressure precipitator and expanded through heating coils to vaporize the solvent, leaving behind the liquid lubricating oil free of asphalt. The vapors are recompressed and cooled to liquefy them and are then returned to the system. The lubricating oil fraction produced may then be distilled at atmospheric pressure by conventional methods of distillation, such as the tube still or the shell still with proper rectification or fractionating equipment to produce any desired cut of lubricating oil.

Any contained wax may be extracted and the oil treated with acid. I prefer to distill the oil 25 to leave a residue which contains the fractions having a viscosity above 400 to 500 seconds Saybolt Universal at 100° F. In other words, the degree of distillation should leave a residue such that if it were redistilled the first fractions taken overhead would be about 600 to 800 seconds Saybolt Universal at 100° F. These figures are by their very nature approximate since they must overlap and the spread of the cut will be dependent on the percentage taken overhead. This 30 will result in a minimum deterioration of the desirable temperature viscosity characteristics. Obviously, the oil may be more deeply topped, i. e. higher viscosity oils may be taken overhead if a partial sacrifice of those desirable qualities 35 is not uneconomic. It is to be noted that the above criteria will hold both for batch and for flash distillation within reasonable commercial limits. It is preferred to top the crude so as to leave behind a residue which on extraction, as 40 above, leaves a lubricating oil of the desired viscosity. However, the process may be run as well by topping the crude as far as possible, i. e. without injuring the paraffin base characteristics, extracting the residue to remove the asphalt, 45 treating the distillate and residue with acids, alkali and/or clay and then blending to the desired viscosity.

The following is a description of a preferred method for treating a mixed base oil, i. e., one 55 containing asphalt and wax, wherein the asphalt is precipitated under conditions such as to leave the wax and oil in the propane solution. Advantage is taken of the propane solution to permit a continuous acid treatment and alkali treatment of the oil. This is a particular advantage of this process since it permits rapid settling of the sludge. The extreme volatility of the propane is used to act as a refrigerant to cause separation of the wax. The process will be more particularly described by reference to Fig. 2.

The modification shown in Fig. 2 is described in my copending application, Serial No. 694,839, filed October 23, 1933, of which the present application is a continuation in part.

Referring to Fig. 2, topped residuum stored in tank 37' is sent by pump 38', and meets liquid propane containing a small amount of oil coming through line 48'. The preferred fraction is that 75

obtained as an overhead in the stabilization of natural gas gasoline. The mixture of propane and residuum pass through mixing coil 39' into decanter 40', where the asphalt in the topped 5 residuum is precipitated and settles rapidly as a slurry. From the bottom of decanter 40', the asphalt slurry is pumped by pump 41' to meet fresh liquid propane introduced by pump 46' via line 47' from propane storage 48'. The asphalt 10 slurry and fresh liquid propane are sent through mixing coil 42' into decanter 43'. The asphalt propane slurry from the bottom of decanter 43' is drawn off through line 145' for recovery of asphalt and propane.

15 The overflow from decanter 43', containing the oil and wax is sent by pump 44' through line 45' to be mixed with the topped residuum and sent into decanter 40', as explained above. The overflow from decanter 40' consisting of propane and 20 lubricating oil stock in the desired ratio is sent through pump 51' for the acid and alkali treatment of the extracted lubricating oil stock. The countercurrent washing of the precipitated asphalt illustrated by the above method of operation 25 may be extended to as many steps as desired, but in general two decanters giving two countercurrent washings will be sufficient to produce an asphalt satisfactorily free of wax and oil.

To the propane solution of extracted lubricating stock, acid from tank 52' is added to mixer 55' by means of pump (or acid egg) 53', and the flow is controlled also by valve 54'. The propane solution and acid are forced by pumps 51' and 53' through mixing coil 55' into decanter 60' where 30 the acid sludge settles rapidly. The addition of the acid in several dumps without drawing the sludge between dumps may be accomplished by tapping mixing coil 55' at various points and introducing acid at these points. The addition of 35 acid in several dumps with the withdrawal of sludge between dumps may be accomplished by means of additional mixing coils and acid decanters. The acid treated oil solution from decanter 60' flows continuously through line 62' 40 into decanter 63', where water is introduced as a spray through line 68' from water storage 64' through pump 65' and valve 67' and acid reaction products are withdrawn through line 56' controlled by valve 57'. The water washed oil overflows from decanter 63' and is sent by pump 69' 45 to be treated. Water is withdrawn via line 58' controlled by valve 59'. The soda solution contained in tank 70' is introduced by pump 71' through line 72' controlled by valve 73'. The 50 mixture of oil solution and aqueous alkali solution is forced through mixing coil 74' into decanter 75' where the caustic solution separates from the propane solution of the oil, and is withdrawn through valved line 76'. The overflow 55 from decanter 75' goes through line 77' to decanter 78', where water is introduced through spray 79' by means of pump 65' through valve 66'. The separated water wash is withdrawn through 60 valved line 80'. The use of propane as a solvent permits the continuous and rapid treatment of lubricating stock in the manner just described.

The neutralized and water washed oil solution overflowing from decanter 78' is carried by line 70 81 to tank 82. The oil in 82 is then treated

for removal of solvent and wax as in Fig. 1 or in any convenient way.

The asphaltic material from separator 43' is withdrawn through line 145'.

The above descriptions are merely illustrative of the mode of employing my invention and are not to be construed as limiting as many variations will appear to those skilled in the art within the scope of my invention which I claim to be:

1. The process for the production of lubricating oil from an oil containing the same which comprises mixing said oil with a liquefied normally gaseous hydrocarbon solvent under superatmospheric pressure sufficient to maintain said solvent liquid, treating said oil dissolved in said solvent with a mineral acid and separating said solvent from the treated oil. 10

2. A process as claimed in claim 1 in which the liquefied normally gaseous hydrocarbon contains a major portion of hydrocarbons having less than 20 four carbon atoms.

3. A process as claimed in claim 1 in which the liquefied normally gaseous hydrocarbon contains a major portion of hydrocarbons of less than three 25 carbon atoms.

4. A process as claimed in claim 1 in which the liquefied normally gaseous hydrocarbon contains a major portion of propane.

5. A process as claimed in claim 1 in which the liquefied normally gaseous hydrocarbon is propane. 30

6. A process as claimed in claim 1 in which the liquefied normally gaseous hydrocarbon is a hydrocarbon selected from the methane series.

7. A process for the production of lubricating oil from an oil containing the same which comprises mixing said oil with a liquefied normally gaseous hydrocarbon solvent under superatmospheric pressure sufficient to maintain said solvent liquid, treating said oil dissolved in said solvent 40 with sulphuric acid, and separating the solvent from the treated oil. 35

8. A process as claimed in claim 7 in which the liquefied normally gaseous hydrocarbon is selected from the methane series. 45

9. A process as claimed in claim 7 in which the liquefied normally gaseous hydrocarbon is propane.

10. A process as claimed in claim 7 in which the liquefied normally gaseous hydrocarbon contained 50 a major portion of hydrocarbons of less than four carbon atoms.

11. A process as claimed in claim 7 in which the liquefied normally gaseous hydrocarbon contains a major portion of propane. 55

12. A process as claimed in claim 1 in which the acid treated oil is treated with alkali.

13. A process as claimed in claim 7 in which the acid treated oil is treated with alkali.

14. A process as claimed in claim 7 in which the lubricating oil mixed with the liquefied normally gaseous hydrocarbon is cooled prior to treatment with sulphuric acid. 60

15. A process as claimed in claim 7 in which the lubricating oil mixed with the liquefied normally gaseous hydrocarbon is cooled by vaporizing a portion of the liquefied normally gaseous hydrocarbon under reduced pressure prior to treatment with sulphuric acid. 65
